UNITED STATES PATENT OFFICE.

JOHN J. COFFEY, OF BROOKLYN, NEW YORK.

WASHBOARD.

1,187,264.

Specification of Letters Patent. Patented June 13, 1916.

Application filed August 24, 1915. Serial No. 47,112.

To all whom it may concern:

Be it known that I, JOHN J. COFFEY, a citizen of the United States, and a resident of Brooklyn, in the county of Kings and State of New York, have invented a new and Improved Washboard, of which the following is a full, clear, and exact description.

This invention relates to washing and scrubbing and has particular reference to 10 the construction of wash boards.

Among the objects of the invention is to improve the construction of a wash board with respect to simplicity and strength of construction and its sanitary nature in 15 practice.

With the foregoing and other objects in view the invention consists in the arrangement and combination of parts hereinafter described and claimed, and while the invention is not restricted to the exact details 20 of construction disclosed herein, still for the purpose of illustrating a practical embodiment thereof reference is had to the accompanying drawings, in which like reference 25 characters designate the same parts in the several views, and in which—

Figure 1 is a front elevation of a preferred embodiment of the invention one corner being broken away; Fig. 2 is a vertical section on the line 2—2 of Fig. 1; Fig. 3 is a transverse sectional detail of the line 3—3 of Fig. 1; Fig. 4 is a perspective detail of the rubbing surface shown in Fig. 1; and Fig. 5 is a similar view of a modified form.

Referring more particularly to drawings, I show a wash board construction comprising a frame composed of wood or other suitable rigid material and including side rails 10, a top rail 11, and a plurality of 40 stiffening rods 12 and 13, extending transversely between the side rails. I prefer to use two of the bars 12 arranged in the same horizontal plane just below the top of the frame and in front of and at the rear of the 45 central plane of the structure. These bars 12 therefore, serve not only as stiffeners or reinforcement means for the frame but also as temporary holders for the bar of soap or the like in practice.

The side rails and the top rail are rabbeted or grooved at 10' and 11' respectively 50 for the reception of the body portion of the device, said body comprising a filler 14 consisting of a sheet of wood or its equivalent 55 extending laterally into the rabbets 10' and 11' and faced front and rear with a double

rushing surface of sheet metal or its equivalent and including a front face 15 and a rear face 16 connected by a loop 17 embracing the rod 13 where the face plate passes 60 around the lower edge of the filler. At the sides and top the rubbing surface is co-extensive with the filler and hence projects into the rabbets aforesaid on both sides of the filler making a close snug neat fit in the 65 side and top rails, such connection being made secure and permanent by the rods 12 and 13.

The front rubbing face 15 comprises a corrugated portion 15^a, side flanges 15^b and 70 a smooth upper panel 15^c, spaced rearwardly from one of the rods 12. As indicated in Figs. 1 and 4 the corrugations 15^a are of isosceles triangular form in cross-section with the ends thereof beveled off as shown 75 at 18. The margins 15^b are wide enough to allow considerable clearance between the beveled ends 18 and the side rails allowing free drainage space for the suds, and since the rubbing surface is fitted snugly in the 80 rabbets 10' and no sharp corners are left at the ends of the corrugations there is no place for the collection and retention of lint, dirt or the like. The back face 16 also is corrugated and may be formed of the corrugated 85 part and also the smooth panels 16^b and 16^c the same as the front face. A loop 17 makes a strong and smooth connection embracing the bar 13.

In the modification of Fig. 5 the rubbing 90 surface is constructed of a continuous piece of sheet metal or its equivalent, including triangular corrugations 20, a smooth side margin 21 and a forwardly projecting semi-cylindrical bead 22. The margin 21 is wide 95 enough to insure a clear space between the bead and the side rail adjacent thereto. The depth of the bead is substantially equal to the altitude of the corrugations.

A device made in accordance with this 100 disclosure is not only clean and sanitary but practically indestructible so long as it is used with care.

I claim—

In a wash board, the combination of side 105 and top rails, a pair of transverse stiffening rods extending from one rail to the other in the same horizontal plane and a body comprising a filler and front and rear sheet metal rubbing surface secured between the side rails and midway between and spaced 110 from said rods, the corrugations of the rub-

bing surfaces having their ends clear of and spaced laterally from the side rails, there being a semi-cylindrical bead formed along the ends of the corrugations and of a 5 depth substantially equal to the altitude of the corrugations.

In testimony whereof I have signed my

name to this specification in the presence of two subscribing witnesses.

JOHN J. COFFEY.
